CLAIM

The ornamental design for a ballistic armor back plate, as shown and described.

DESCRIPTION

FIG. 1 is a front isometric view of the ballistic armor back plate of this invention;

FIG. 2 is a top plan view thereof;

FIG. 3 is a front elevational view thereof;

FIG. 4 is a left side view thereof, the right side view being a mirror image thereof;

FIG. 5 is a rear elevational view thereof; and,

FIG. 6 is a bottom plan view.
